GAUGE FOR ALIGNING A STRING OF PIPE
WITH A GRADE LINE

John A. Mitchell, Mount Pleasant, Pa.

Application October 25, 1949, Serial No. 123,443

3 Claims. (Cl. 33—180)

1

The present invention relates to an instrument and more particularly to an instrument to be used with a grade line.

In the laying of pipe in a trench, such as water and sewer pipe, the method used today is to erect batter boards, and stretch a grade-line string between them. The bases of the batter boards are placed transversely across a trench on the surface of ground, one edge of the uprights being on the center line of a trench, and the string stretched so that it is over the center line of the trench and against one edge of the uprights. A staff with grade line marked thereon is used for setting pipe in the trench to grade.

This arrangement interferes with various methods that are employed for lowering pipe into a trench, an example being pulley and tackle. Workmen when using such equipment, and oftentimes the tackle or pipe, will become engaged with the grade string, thus fouling same. This causes loss of time for the reason the grade line has to be re-established.

It is therefore an object of the present invention to provide an instrument so designed that the grade line may be offset from the center line of a trench.

Another object of the present invention is the provision of a grade instrument that will permit the erection of batter boards on one side of a trench.

A still further object of the present invention is the provision of a grade instrument or staff having horizontal adjustable means.

A still further object of the present invention is the provision of a grade instrument or staff having vertical adjustable means.

A still further object of the present invention is the provision of a grade instrument or staff having adjustable means for engagement with a grade line that is offset from the center of a trench.

A still further object of the present invention is the provision of means on the staff for adjusting the staff in the vertical, horizontal or at an angle.

With these and other objects in view, the advantages of the present invention will become more fully apparent as reference is made to the accompanying drawing, in which:

Figure 1 is a front elevational view of the staff

2

and illustrating the vertical and horizontal adjusting means.

Figure 2 is a rear elevational view of the staff and the adjustable means.

Figure 3 is a side elevational view of the staff.

Figure 4 is a top plan view of Figure 1 and illustrating the adjustable arm in an extended position, the figure being enlarged, with parts omitted.

Figure 5 is a sectional view taken on line 5—5 of Figure 1, illustrating the adjustable arms and plate, the figure being enlarged.

Figure 6 is an elevational view of the T-shaped plate member.

Figure 7 is a transverse sectional view of a trench and illustrating the batter boards, grade line, pipe and staff.

Figure 8 is a longitudinal sectional view of a trench and illustrating the application of the device to pipe and grade line.

Referring to the drawing the numeral 10 represents the device and it comprises a staff having a body 11 of solid or tubular material and a base 12, and reinforcing arms 13 that may be secured to the base and body by screws or by spot welding. To one face of the body 11 there is secured by screws 14 a handle 15, and to another face of the body 11 there is secured by screws 16 a spirit level 17 having bubbles 18, 19 and 20. A plurality of apertures 21 and 22 are provided in two side faces of the body and they are in axial alignment.

Mounted for adjustable and slidable movement on the body on its upper portion is a sleeve 23 having ends 24 and 25, end 24 being provided with a through aperture that receives a bolt 26 adapted for engagement with one of the apertures 21 for locking engagement by a nut 27 to the body 11. Between the ends 24 and 25 there is a reduced portion 28, this portion being integral with the ends 24 and 25. The end 24 is provided with an arm 29 that is integral with it, and it is provided with a plurality of apertures 30, the arm 29 being adapted to be positioned on the staff either on the left or right side due to the sleeve 23 being slidable on the shaft. Mounted on arm 29 is a slidable arm 31 having guide lugs 32, the end 33 of the arm being disposed at a right angle. The slidable arm 31 is provided with an aperture that receives a bolt

34 that secures a plate 35 having a slot 36 to the arm, the plate due to the slot 36 being adjustable vertically. A nut 37 on the bolt 34 locks the plate to the arm, the slidable arm 31 being secured to the arm 29 by bolt 38 and nut 39.

Below the spirit level 17 there is mounted a strap 40 having horizontal arms 41, a central aperture 42, a plurality of apertures 43 and a vertical portion 44 that serves to hold the strap to one face of the body 11. The horizontal arms 41 of the strap are engaged by a plate 45 having a central aperture that is aligned with the aperture 42, a bolt 46 passing through the apertures 42 and aligned aperture in plate 45 and receiving a nut 47 that secures the strap to the body 11. The plate 45 is provided with finger lugs 48, the inner edges of the finger lugs impinging side walls of the body 11, the finger lugs serving as a clamping means for the strap. The strap 40 is adjustable vertically on the body 11 due to the plurality of apertures 22. Mounted on the arms 41 of the strap 40 are extension arms 49 that may be of any suitable length, having at one end guide lugs 50 that hold the extension arms 49 for slidable movement on the arms 41, the opposite end 51 of the extension arms 49 being disposed at right angles thereto. As shown in Figure 5 the extension arms 49 are extended and they are secured to arms 41 by bolts 52 that engage apertures 43, the bolts being secured by nuts 53.

In Figures 7 and 8 which are diagrammatic, the numeral 55 represents ground level, 56 a trench and 57 the bottom of the trench. On one side of the trench batter boards 58 are erected at designated distances, the batter boards comprising vertical stakes 59 driven into the ground, and a cross arm 60 secured to the stakes, the cross arm being on an approximate grade. The end 61 of the cross arm has positioned thereon a string 62 that establishes the grade line.

To use the device after a trench has been dug, batter boards 58 are erected at designated distances on one side of a trench, and at one end 61 of the cross arms 60 that are secured to stakes 59 there is positioned a grade line string 62.

In the use of the device, pipe 65 may be upended or placed horizontally on the ground, the strap 40 having horizontal arms 41 and 49 being adjusted up or down until the arms are approximately on the horizontal diameter of pipe 65, the arm 49 then adjusted to the inner diameter of the end 65 of the pipe or to the inner diameter of the bell 67, the bolts 52 inserted and passed through apertures 43, through the aligned apertures in the ends of the arms 49, and the nuts 53 tightened, thus securing the extension arms 49 to the arms 41. If desired the arms 49 may be adjusted to proper diameter by using a rule.

After the above operation the sleeve 23 is moved up or down on the staff 11 until the arm 29 is at the proper grade level, the bolt 26 is then passed through the apertures in the end 24 and the apertures 21 in the body 11 of the staff 10 and the nut 27 then tightened. The slidable arm 31 is next adjusted until one edge of the plate 35 engages the grade line string 62, the bolt 38 placed in the apertures in the arms 29 and 31 and secured by the nut 39.

As indicated by the arrow in Figure 8, pipe is laid in the direction of the arrow, gravel or cement placed on the floor 51 of trench 56, pipe 65 then lowered into the trench, the base 12 of the staff 10 placed in the pipe (as shown in Figure 8) and gravel or cement adjusted until

the bottom of the slidable arm 31 and the edge of the plate 35 engage the grade line string 62. One of the levels will indicate if the staff is being held in vertical position.

The handle 15 provides a means for holding the staff in a vertical position or in an angular position, the position being established by the bubbles 18, 19 and 20. The handle also provides a means for moving the staff 10 along various stations and to the pipes as they are laid in a trench.

From the above description it can be seen, and as illustrated in Figure 7, the grade line is offset from the center of the trench, and by the provision of arms 29 and 31, and arms 41 and 49, pipe will always be laid on the center line of a trench and at the exact depth grade.

The grade line establishes the rate of grade to which pipe is to be laid. The staff and its adjustable arms are set, one for the rate of grade, the other for the diameter of the pipe, the base of the staff or body to engage the inner diameter of the pipe. The pipe is adjusted as to elevation by bringing the inner diameter of the pipe to the base 12 of the body 11, the distance of grade being the distance between the base 12 and the bottom edge of the slidable arm 31, and one edge of the plate 35, the arm 31 having been set for the exact grade on the body 11.

While the invention has been disclosed in connection with certain specific embodiments thereof, it is to be understood that these are by way of example rather than by way of limitations and that the invention is to be defined by the attendant claims which should be given a scope as broad as is consistent with the prior art.

What is claimed is:

1. A grade instrument for aligning a string of pipe with a grade line string comprising a body, upper and lower arms carried by said body and adapted for vertical and horizontal adjustment on said body, a base on said body disposed rearwardly of the front face of said body and engageable with the inner peripheral wall of a pipe, and a member adjustably mounted on and at right angles to said upper arms, one edge of said member and one edge of one of said upper arms contacting the grade line string to determine the proper position for a pipe in a trench.

2. A grade instrument for aligning a string of pipe with a grade line string comprising a body, upper and lower arms carried by said body and adapted for vertical and horizontal adjustment on said body, a base on said body disposed rearwardly of the front face of said body and engageable with the inner peripheral wall of a pipe, and a member adjustably mounted on and at right angles to said upper arms, one edge of said member and one edge of one of said upper arms contacting the grade line string, said lower arms on said body being adjustable horizontally to the diameter of a pipe to position said body centrally of said pipe and thereby enable pipe to be laid to the exact grade of a grade line string.

3. A grade instrument for aligning a horizontal pipe with a horizontal grade line string above said pipe and offset with respect thereto, comprising a vertical body, a sleeve slidably adjustable vertically on the upper end of said body, an upper arm mounted on said sleeve and horizontally adjustable thereon, a slotted plate carried by said upper arm and vertically adjustable thereon, said plate being adapted to engage the grade line string, a strap carried by said body

at the lower end of said body and vertically adjustable thereon, and a pair of lower arms carried by said strap and horizontally adjustable thereon, the ends of said lower arms extending equidistantly from the body and being adapted to engage the inner rim of the pipe.

JOHN A. MITCHELL.
